UNITED STATES PATENT OFFICE.

WILLIAM ECKSTEIN, OF LONDON, ENGLAND.

METALLIC LATHING.

SPECIFICATION forming part of Letters Patent No. 514,313, dated February 6, 1894.

Application filed October 3, 1893. Serial No. 487,058. (No model.) Patented in England June 11, 1892, No. 11,086.

To all whom it may concern:

Be it known that I, WILLIAM ECKSTEIN, of 187 Union Street, London, S. E., in the county of Surrey, England, have invented a new and useful Improvement in Metallic Lathing, (for which I have obtained Letters Patent in Great Britain, No. 11,086, dated June 11, 1892,) of which the following is a full, clear, and exact description.

10 The invention relates to metallic lathing having means such as keys, loops, or spurs, for causing the plaster when applied thereto, to be interlocked with such lathing. Various forms of plaster-engaging devices have 15 been provided, and the present invention has for its object to improve and make more efficient such plaster engaging devices, and at the same time greatly increase the rigidity of the plate.

20 The invention consists in the novel construction hereinafter particularly described and defined in the claim.

Reference is to be had to the accompanying drawings forming a part of this specification, 25 in which similar letters of reference indicate corresponding parts in all the figures.

Figure 1, is a broken front view of a piece of my improved lathing. Fig. 2, is a plan or top edge view thereof, as indicated by the arrow in Fig. 1. Fig. 3, is a vertical section on line 3—3, Fig. 1; and Fig. 4 is a perspective view of a piece of the lathing.

It will be understood that both sides of the plate are similar and that the plate consequently may be secured with either face as the front, and the reference made hereinafter to the front and the inward and outward bulging of the loops, is arbitrary and in the interest of intelligent description.

40 In producing metallic lathing in accordance with my invention, a plate A, of thin sheet metal, is formed with broad or large corrugations $a, a', a^2, a^3, \&c.$, thereby giving a regular undulating surface on both sides, 45 and in the plate, in each corrugation, transverse slits are produced, and the metal between each pair of slits, is bulged to form loops B, B', which bulge the reverse of the curvature of the corrugation in which they 50 are formed. Thus the loops B, B', of adja-

cent undulations are bulged in opposite directions from the plane of the plate; that is, the undulation a , is outward and the loops B therein are bulged inward, as seen in front view, Fig. 1, and top edge or plan view, Fig. 55 2, while the undulation a' , which curves inward, has its loops B' bulged outward and so on. In this way the plate is made exceedingly rigid, as the bulged loops as thus disposed will resist bending in both directions, 60 and the rigidity is further increased by forming the loops so that the ends of each undulation join the plate in the next adjacent undulation, at points within the line of the loops of the said adjacent undulations, that is, the 65 ends b , of one set of loops, are not in alignment longitudinally of the corrugation, with the ends of adjacent series of loops, but within the line of juncture of the latter, so that the loops break joint so to speak, and in this way 70 no continuous weak lines are present on which the plate might have a tendency to yield, such as the very numerous openings might otherwise produce. It will further be seen by reference to Figs. 2 and 3, that I bulge the loops 75 of each undulation beyond the plane of projection of the next adjacent undulations, thereby providing openings sufficiently large for the plaster to find its way in proper quantity to effect an increased interlocking engagement with the undulations and the loops. 80

Having thus fully described my invention, I claim as new and desire to secure by Letters Patent—

Metallic lathing consisting of a corrugated 85 plate, having plaster-engaging loops projecting from opposite sides and extending transversely across said corrugations, and bulging reversely to the latter, the ends of said loops or their points of attachment to the plate on 90 one side of the same being located beyond the line of the ends of the adjacent loops on the opposite side of the plate, whereby the mean thickness of the plate is increased, as shown and described.

WILLIAM ECKSTEIN.
